Inventor:
Ira Hann

UNITED STATES PATENT OFFICE.

IRA HANN, OF HOPE, NEW JERSEY.

WASHING-MACHINE.

Specification of Letters Patent No. 26,430, dated December 13, 1859.

To all whom it may concern:

Be it known that I, IRA HANN, of Hope, county of Warren, in the State of New Jersey, have invented new and useful Improvements in Washing-Machines; and I do hereby declare that the following is a full and exact description thereof, reference being had to the accompanying drawings, and to the letters of reference marked thereon.

10 The nature of my invention consists in certain improvements in washing machines as hereinafter described.

In the accompanying drawings forming part of this specification, Figure 1, represents an isometrical perspective view of my improved machine. Fig. 2, represents a vertical longitudinal section through the center of the same.

Similar letters denoting the same parts in the different views, A, represents the body of the machine which is the form of a rectangular box and is supported upon suitable legs s, s, s, s; in the bottom of the body A, is fixed a permanent rubber board n, with 25 parallel transverse corrugations.

m, is the moving rubber board which has its under surface (that which is adjacent to the board, n, when in operation) corrugated in a manner similar to the upper surface of 30 the board, n. The rubber, m, is operated by means of a rocking lever, M, which is connected thereto by means of branch connecting rods, o, and which has its fulcrum (at its lower end) in a stand, N, which projects 35 from the end of the body, A.

D, is a standard which projects up from one side of the body A, and E, another standard projecting up from one end. The top of the standard D, is slotted out to accommodate a lever B, which has a slot b, 40 cut in it to work around the pivot passing through it and the standard D. This lever D, extends sufficiently forward to be readily grasped by the operator who moves the rocking lever M, and extending some distance beyond the rear end of the machine is at its extremity coupled by a link joint to the rear end of the lever F, this lever F, is coupled 45 at its other end to a "presser carriage" a, and is pivoted near its center in the standard E. The presser carriage consists of a simple frame a, carrying two short cylinders or friction rolls b', b', (one at each end) which bears on the upper surface of the rubber 50 board m.

The operation of my improved machine is as follows: The body, A, being supplied with a suitable quantity of water the lever, M, is pulled forward (toward the operator who stands at that end of the machine where 55 the lever, M, is pivoted) the forward end of lever, B, thrown up and the rubber board, m, raised out of the body, A, as illustrated by red lines in Fig. 2. The articles to be washed are then placed upon the 60 board, n, and the board, m, placed within the body, A, again; as illustrated by the black lines in Figs. 1 and 2; and on top of the articles. The operator then grasps the forward end of lever, B, with the left hand 65 and the lever, M, with the right hand and while pulling down upon the lever, B, moves the lever, M, back and forth; by this process the rubber board, m, is caused to reciprocate over and against the articles 70 between it and the board, n; while said board, m, is pressed down against the articles being rubbed with just such amount of force as the operator shall see fit to exert (according to circumstances) with the left hand on 75 the lever, B.

It will be seen, that while the rubber board, m, is caused to reciprocate, it may be made to exert any desired pressure on the clothes, and that by virtue of the combination of levers, and the construction of "presser carriage" such result is accomplished in a desirable manner without much friction. It will also be observed that while 80 the machine is capable of performing 85 readily the office just described, the parts are so constructed and arranged together that the moving rubber, carriage, &c., are readily thrown out of the way for the insertion or extraction of the clothes.

95 What I claim as new and desire to secure by Letters Patent is—

The combination of the fixed rubber board, n, with the removable rubber, m, "friction roll" pressure carriage, a, b, and 100 operative levers, F, B, and M; the whole arranged and operating as specified for the purposes described.

105 In testimony whereof I have hereunto set my hand and seal this second day of June 1859.

IRA HANN. [L.S.]
